UNITED STATES PATENT OFFICE

145,868

DESIGN FOR A HOLDER FOR FLOWERS OR OTHER SLENDER ARTICLES

Frank P. Fletcher, Pasadena, Calif.

Application August 1, 1945, Serial No. 121,142

Term of patent 14 years

(Cl. D35—3)

To all whom it may concern:

Be it known that I, Frank P. Fletcher, a citizen of the United States, residing at Pasadena, in the county of Los Angeles and State of California, have invented a new, original, and ornamental Design for a Holder for Flowers or Other Slender Articles, of which the following is a specification, reference being had to the accompanying drawing, forming part thereof.

Fig. 1 is a top plan view of a holder for flowers or other slender articles illustrating my new design;

Fig. 2 is an end elevational view thereof;

Fig. 3 is a side elevational view thereof;

Fig. 4 is another end elevational view thereof and is taken in a direction opposite to that of Fig. 2;

Fig. 5 is a bottom plan view thereof; and

Fig. 6 is a perspective view thereof.

I claim:

The ornamental design for a holder for flowers or other slender articles, as shown.

FRANK P. FLETCHER.
